UNITED STATES PATENT OFFICE.

JOHN J. PARKINSON, OF CHICAGO, ILLINOIS.

HEATING COIL FOR HOT-WATER SYSTEMS.

Application filed August 9, 1923. Serial No. 656,516.

My invention relates to improvements in hot water systems, and it consists in the combinations, constructions, and arrangements herein described and claimed.

5 An object of my invention is to provide a novel heating coil or tube in a hot water system in which the water heating coils are immersed in the water within the boiler, whereby the pipes will not immediately cool as 10 soon as the fire goes out, as is the case when the coils are disposed in the fire box, but will remain hot and will continue to warm the water therein until the water in the steam boiler is the same temperature as the water 15 within the coil pipes.

A further object of my invention is to provide a device of the character described in which the heating coils will not be burnt out through use, since they are immersed in the 20 water in the boiler and cannot therefore be raised above a predetermined temperature.

A further object of my invention is to provide a device of the character described which is simple in construction, and durable 25 and efficient for the purpose intended.

Other objects and advantages will appear in the following specification, and the novel features of the invention will be particularly pointed out in the appended claims.

30 My invention is illustrated in the accompanying drawings, forming part of this application, in which

Figure 1 is a front elevation of the device, Figure 2 is a section along the line 2—2 of 35 Figure 1, and

Figure 3 is a section along the line 3—3 of Figure 1.

In carrying out my invention, I provide a steam boiler 1 which has a fire box 2, fire tubes 3, and a water containing cylinder 4. The fire tubes 3 are submerged in the water 5 of the cylinder. The hot gases of combustion pass from the fire box 2 through the fire tubes or flues 3 and into the chimney 6. The 45 heat given up by the gases as they pass from the flues 3 passes into the water 5 and raises the temperature thereof. A grate (not shown) is usually provided beneath the fire box 2 so as to remove the ashes from the fire box as they accumulate.

I dispose a tube 7 in the cylinder 4 and submerge it beneath the water 5, as is clearly shown in Figure 2. The tube 7 has a partition 8 therein that runs substantially the entire length of the tube. The tube 7 is closed 50 at its inner end, as at 9, and the partition 8

stops a short distance from the end 9, as at 10, whereby a continuous passageway is provided through the lower half of the tube to the end 9 and back to the outer end of the 60 tube 7 along the upper half of the tube. A cross fitting 11 having four openings therein is secured to the outer end of the pipe 7. A pipe 12 communicates with one of the openings in the cross fitting 11 and also communicates with a water reservoir 13. A second pipe 14 communicates with another one of the openings in the cross fitting 11 and is connected at its other end with the lower end of the reservoir 13. It will be noted from 70 Figure 1 that the pipe 12 communicates with the reservoir 13 at the top thereof and the pipe 14 communicates with the reservoir at the bottom thereof.

In Figure 3 I have clearly shown a partition 15 in the cross fitting 11 that is adapted to direct the water from the pipe 14 into the lower half of the pipe 7 and to direct the water from the upper half of the pipe 7 into the pipe 12. A plug 16 closes one of the 75 openings in the cross fitting 11. The partition 15 is spaced slightly from the partition 8 so as to provide an air passage 17 which prevents the pipe 7 from becoming air bound and thus prevent circulation of the water. 80 If it were not for this passage 17, the air collected in the pipe 7 when the water is drained therefrom would likely become trapped in the pipe and would therefore prevent circulation of the water through the 85 pipe. The passage 17 permits this air to escape directly to the pipe 12, thus allowing the water to enter the pipe 7.

From the foregoing description of the various parts of the device, the operation thereof may be readily understood. A water inlet pipe 18 is connected with a source of supply (not shown) and communicates with the bottom of the reservoir 13. A hot water outlet 19 communicates with the top of the reservoir 13 and is connected with the piping of a house. When a fire is built in the fire box 2, the water 5 is heated by means of the hot gases passing through the flues 3. This hot water in turn heats the water within the pipe 7 and causes a flow in the upper half of the pipe 7 in the direction of the arrow. This flow is due to the fact that the water in the pipe 7 expands when heated and therefore flows upwardly through the pipe 12 and into the reservoir 13. The cold water from the lower portion of the reservoir 13 flows 100 105 110

through the pipe 14 and into the lower half of the pipe 7 to take the place of the water that has flowed from the pipe 7 to the reservoir. As long as the water 5 is hotter than the water in the reservoir 13, there will be a continuous flow of water from the reservoir to the pipe 7 and back to the reservoir again. It is obvious that the pipe 7 cannot be heated to such a high degree of temperature as to 10 burn away the pipe, since the pipe is submerged in the water 5 and does not come into direct contact with the flames, as is the case when the heating coils are disposed in the fire box 2. The pipe 7 will therefore have a 15 very long life. Nor will steam be formed in the pipe 7 since the water pressure is usually considerably greater than the highest steam pressure present in the boiler.

Furthermore, the water within the pipe 7 20 will continue to be heated for a considerable length of time after the fire in the fire box 2 has gone out due to the fact that the water 5 remains hot for quite a while after the fire has gone out.

25 The water in the reservoir 13 is under the same pressure as the water in the pipe 18, this pressure being sufficient to force the water through the pipe 19 and into the piping system of the house. As fast as the 30 water is drawn from the pipe 19, cold water flows into the reservoir 13 through the pipe 18. This water is directed to the pipe 7 by means of the pipe 14.

In case the pipe 7 becomes clogged with 35 foreign matter, it is merely necessary to

close the gate valve 20 and to open the sediment cock 21. The pressure within the reservoir 13 will reverse the former flow of the water and will cause it to pass through the pipe 12, through the pipe 7, the pipe 14, and 40 out through the sediment cock 21. A comparatively small amount of water in the reservoir 13 is sufficient to thoroughly cleanse the pipe 7. When all of the foreign matter has been drained off, the sediment cock 21 is 45 closed and the gate valve 20 opened, whereupon the normal circulation of the water is resumed. The reservoir 13 is also provided with a sediment cock 22 by means of which the entire contents of the reservoir can be 50 drained if desired.

The device may be readily installed in homes and hotels with but slight alterations being necessary in the steam boilers used in these places.

I claim:

In combination with a tube adapted to be disposed in the water in a boiler and having a partition therein dividing the tube into water traversing compartments arranged in 60 series, a fitting connected to said tube and having a cold water inlet, and a hot water outlet, a partition in said fitting separating the cold water inlet from the hot water outlet, said partition being slightly spaced 65 from the front edge of the partition in said tube to prevent the trapping of air in said tube.

JOHN J. PARKINSON.

CERTIFICATE OF CORRECTION.

Patent No. 1,663,562.

Granted March 27, 1928, to

JOHN J. PARKINSON.

It is hereby certified that error appears in the printed specification of the above numbered patent requiring correction as follows: Page 1, line 51, after the word "tube" insert the words "or heating coil"; and that the said Letters Patent should be read with this correction therein that the same may conform to the record of the case in the Patent Office.

Signed and sealed this 8th day of May, A. D. 1928.

M. J. Moore,

Acting Commissioner of Patents.

through the pipe 14 and into the lower half of the pipe 7 to take the place of the water that has flowed from the pipe 7 to the reservoir. As long as the water 5 is hotter than the water in the reservoir 13, there will be a continuous flow of water from the reservoir to the pipe 7 and back to the reservoir again. It is obvious that the pipe 7 cannot be heated to such a high degree of temperature as to 10 burn away the pipe, since the pipe is submerged in the water 5 and does not come into direct contact with the flames, as is the case when the heating coils are disposed in the fire box 2. The pipe 7 will therefore have a 15 very long life. Nor will steam be formed in the pipe 7 since the water pressure is usually considerably greater than the highest steam pressure present in the boiler.

Furthermore, the water within the pipe 7 20 will continue to be heated for a considerable length of time after the fire in the fire box 2 has gone out due to the fact that the water 5 remains hot for quite a while after the fire has gone out.

25 The water in the reservoir 13 is under the same pressure as the water in the pipe 18, this pressure being sufficient to force the water through the pipe 19 and into the piping system of the house. As fast as the 30 water is drawn from the pipe 19, cold water flows into the reservoir 13 through the pipe 18. This water is directed to the pipe 7 by means of the pipe 14.

In case the pipe 7 becomes clogged with 35 foreign matter, it is merely necessary to

close the gate valve 20 and to open the sediment cock 21. The pressure within the reservoir 13 will reverse the former flow of the water and will cause it to pass through the pipe 12, through the pipe 7, the pipe 14, and 40 out through the sediment cock 21. A comparatively small amount of water in the reservoir 13 is sufficient to thoroughly cleanse the pipe 7. When all of the foreign matter has been drained off, the sediment cock 21 is 45 closed and the gate valve 20 opened, whereupon the normal circulation of the water is resumed. The reservoir 13 is also provided with a sediment cock 22 by means of which the entire contents of the reservoir can be 50 drained if desired.

The device may be readily installed in homes and hotels with but slight alterations being necessary in the steam boilers used in these places.

I claim:

In combination with a tube adapted to be disposed in the water in a boiler and having a partition therein dividing the tube into water traversing compartments arranged in 60 series, a fitting connected to said tube and having a cold water inlet, and a hot water outlet, a partition in said fitting separating the cold water inlet from the hot water outlet, said partition being slightly spaced 65 from the front edge of the partition in said tube to prevent the trapping of air in said tube.
